(74) *Attorney, Agent, or Firm* — ArentFox Schiff LLP

(57) **CLAIM**

The ornamental design for a display screen with icon, as shown and described.

DESCRIPTION

FIG. 1 is a front view of a first embodiment of a display screen with icon showing our new design;

FIG. 2 is a front view of a second embodiment of a display screen with icon showing our new design;

FIG. 3 is a front view of a third embodiment of a display screen with icon showing our new design;

FIG. 4 is a front view of a fourth embodiment of a display screen with icon showing our new design;

FIG. 5 is a front view of a fifth embodiment of a display screen with icon showing our new design;

FIG. 6 is a front view of a sixth embodiment of a display screen with icon showing our new design; and,

FIG. 7 is a front view of a seventh embodiment of a display screen with icon showing our new design.

The broken lines showing an electronic device illustrate environmental subject matter, whereas the broken lines showing a display screen illustrate portions of the article. None of the broken lines form part of the claimed design.

1 Claim, 7 Drawing Sheets

The ornamental design for a display screen with icon, as shown and described.

DESCRIPTION

The patent or application file contains at least one drawing executed in color. Copies of this patent or patent application publication with color drawings(s) will be provided by the Office upon request and payment of the necessary fee.

FIG. 1 is a front view of a first embodiment of a display screen with icon showing our new design;

FIG. 2 is a front view of a second embodiment of a display screen with icon showing our new design;

FIG. 3 is a front view of a third embodiment of a display screen with icon showing our new design;

FIG. 4 is a front view of a fourth embodiment of a display screen with icon showing our new design;

FIG. 5 is a front view of a fifth embodiment of a display screen with icon showing our new design;

FIG. 6 is a front view of a sixth embodiment of a display screen with icon showing our new design; and,

FIG. 7 is a front view of a seventh embodiment of a display screen with icon showing our new design.

The broken lines showing an electronic device illustrate environmental subject matter, whereas the broken lines showing a display screen illustrate portions of the article. None of the broken lines form part of the claimed design.

U.S. Patent

Jul. 19, 2022

Sheet 1 of 7

D958,189 S

FIG. 1

U.S. Patent

Jul. 19, 2022

Sheet 2 of 7

D958,189 S

FIG. 2

U.S. Patent

Jul. 19, 2022

Sheet 3 of 7

D958,189 S

FIG. 3

U.S. Patent

Jul. 19, 2022

Sheet 4 of 7

D958,189 S

FIG. 4

U.S. Patent

Jul. 19, 2022

Sheet 5 of 7

D958,189 S

FIG. 5

U.S. Patent

Jul. 19, 2022

Sheet 6 of 7

D958,189 S

FIG. 6

U.S. Patent

Jul. 19, 2022

Sheet 7 of 7

D958,189 S

FIG. 7
